(57) **CLAIM**

I claim the ornamental design for a tip holder for an oral cleansing device, as shown and described.

DESCRIPTION

FIG. 1 is a top isometric view of a tip holder for an oral cleansing device.

FIG. 2 is a bottom isometric view thereof.

FIG. 3 is a top plan view thereof.

FIG. 4 is a bottom plan view thereof.

FIG. 5 is a front elevation view thereof.

FIG. 6 is a rear elevation view thereof.

FIG. 7 is a right side elevation view thereof; and,

FIG. 8 is a left side elevation view thereof.

The broken lines illustrate portions of the tip holder that form no part of the claimed design.

1 Claim, 5 Drawing Sheets
